UNITED STATES PATENT OFFICE.

JOHN C. WAHL, OF CHICAGO, ILLINOIS, ASSIGNOR TO THE WAHL COMPANY, OF CHICAGO, ILLINOIS, A CORPORATION OF DELAWARE.

MECHANICAL PENCIL.

Application filed April 12, 1924. Serial No. 705,979.

My invention relates to pencils, and primarily to that class of pencils commonly called mechanical pencils. The mechanism for propelling the lead in this application is disclosed and claimed in the application of 5 John Straka, bearing Serial No. 462,146, filed April 18, 1921. Among the objects of this invention is to provide novel means for detachably securing the tip end of the pencil 10 to the barrel; further to provide improved means for securing the eraser cover in operative position; further to provide an improved form of clip attaching means; further to generally improve the construction of pencils of the mechanical type; and such further objects, advantages and capabilities as 15 will later more fully appear.

My invention further resides in the combination, construction and arrangement of 20 parts illustrated in the accompanying drawings, and while I have shown therein a preferred embodiment I wish it to be understood that the same is susceptible of modification and change without departing from the spirit 25 of my invention.

In the drawings:—

Fig. 1 is a longitudinal sectional view of my invention;

Fig. 2 is a view, partially in section and 30 partially in elevation;

Fig. 3 is a fragmentary view of the upper portion of the pencil showing the method of holding a clip in the barrel;

Fig. 4 is a detail view showing the detachable tip, and part of the mechanism for propelling a lead through the barrel of the pencil;

Fig. 5 is a perspective view of the shell on the interior of the barrel of the pencil, and 40 the nut which holds the said shell from longitudinal movement within the barrel;

Fig. 6 is a perspective view of the eraser holding device adapted to be screwed to the top of the shell shown in Fig. 5;

Fig. 7 is a cross section through the line 45 7—7 in Fig. 1, and

Fig. 8 is a cross section through the line 50 8—8 in Fig. 1.

The numeral 1 indicates the metal barrel, 55 or outer shell, of a mechanical pencil constructed in accordance with my invention. The said shell 1 is swedged at its lower extremity to form a shoulder 2. The numeral 3 indicates a shell which is adapted to be inserted in the barrel 1. This shell 3 is swedged

and threaded at its upper extremity, as at 4, and is swedged a little over one half of its length from the lower extremity as is shown in Fig. 5. The lower swedged end of the shell is corrugated in four places as at 5 forming 60 guide ways in the interior thereof, the function of these guide ways to be hereafter described.

The lower end of the shell is threaded as 65 at 6 to receive a correspondingly threaded nut 7 whose function will be hereafter described.

A groove 8 is pressed into the upper and larger part of the shell 3. This groove communicates with the external surface of the lower swedged end of the said shell and is 70 beveled in the upper part of its bottom so that the groove at its upper end is of a depth equal to the thickness of the clip 9, which is adapted to be inserted through the barrel and align with the said groove. 75

An aperture 10 is provided in the bottom of this groove to receive the projection 11 on the inner face of the clip, and an aperture 12 is provided in the barrel to receive a projection 13 on the outer face of the rear end of 80 the clip. It will clearly be seen that when the shank of the clip 9 is inserted through the aperture 14, and the shell 3 is forced into the top end of the barrel 1, that the projection 11 will engage in the aperture 10 in the shell, 85 and thus, with the engagement of the projection 13 with the corresponding aperture 12 in the barrel, the clip will be held securely in place between the barrel and shell without the use of solder or other securing means. 90

Inasmuch as the pressing in of the groove 8 forms a shoulder 15 in the shell it may be seen that the shell may only be inserted in the barrel until this shoulder 15 contacts with the upper end of the clip, thus preventing 95 further downward movement of the said shell, and leaving the swedged and threaded end 4 extending from the top end of the barrel.

An eraser holder 16 interiorly threaded for 100 a portion of its length is provided and is adapted to be screwed on to that threaded portion of the shell which extends out of the barrel. An eraser 17 is seated in the eraser holder 16 and held therein by the inturned 105 edges 18 of the said eraser holder, which holding action is further increased by the friction caused by slitting the eraser holder as at 19, the part on each side of the slit tending to spring together. A groove 20 which en- 110

circles the said eraser holder is provided. This groove is adapted to receive a bead 30 formed on the interior of an ornamental eraser cover 21 thus permitting the eraser cover to be securely fastened to said eraser holder. It will be clearly seen that direct longitudinal pull of the cap will cause the eraser holder to contract through the medium of the slot 19, thus permitting the eraser cover to be withdrawn and afford access to the eraser.

Numeral 22 indicates a swedged tip which is adapted to be inserted over the lower end of the barrel 1, the upper edge of said tip engaging the shoulder 2 of the barrel. This tip 22 is swedged to form a small aperture in its lower end, which aperture receives a steel friction point 23.

Fixedly mounted on the interior of the tip 22 is a tube 24 provided with a spiral slot 25 extending practically its length. Mounted in the said tube and having one of its ends outturned to extend out of the slot 25 in the tube 24 is a feed wire 26 which is adapted to travel up and down to thus propel or permit 25 to be retracted a lead mounted in the tube 24 below the feed wire.

Spiral tube 24 is provided at its upper end with resilient gripping means for holding the tip in operative association with the pencil. In Fig. 1 this gripping means is shown as a tubular head 31 secured to tube 24 by means of a pin 32 inserted into the tube 24 and held there by friction; or as shown in Fig. 4 the gripping head 31 may be formed 35 integral with tube 24. In both forms the gripping head is slotted as shown at 33, and the parts on both sides of the slit slightly spread apart so that when the gripping head is inserted into the lower end of shell 3 said 40 parts will be forced toward each other by contact with ribs 34 formed by pressing inwardly the metal of the shell at grooves 5, and a gripping action thus provided sufficient to hold in place said tube 24, tip 22, 45 and point 23.

Having described my invention, what I claim as new and desire to secure by Letters Patent is:

1. In a mechanical pencil, a barrel, a shell 50 adapted to be inserted in said barrel and provided with inwardly offset elongated members, a tip detachably mounted at one end of said barrel, a tube fixed to said tip and adapted to extend within said shell, and means on 55 said tube to coact with said offset members to detachably hold said tip in operative position.

2. In a device of the class described, a barrel, a shell adapted to be inserted in said barrel and provided with inwardly offset 60 elongated members, a tip detachably secured to said barrel, and a tube fixed at one end to said tip and provided at its opposite end with resilient gripping means to coact with said offset members to permit detachment of said 65 tip.

3. A mechanical pencil comprising a barrel, a shell adapted to be inserted in said barrel and provided with inwardly offset elongated members, a detachable tip mounted at 70 one end of said barrel, a lead receiving and feeding tube secured to said tip, and friction means at the inner end of said tube arranged to coact with said offset members to frictionally hold said tube and tip in operative position, said friction means comprising a slotted head, the members of which are constructed to move toward each other sufficient to cause a sliding friction grip with said offset members when said tube is inserted 75 therein.

4. In a mechanical pencil, a barrel, inwardly offset elongated members in said barrel, a detachable tip mounted on one end of said barrel, an elongated tube fixed to said tip to extend within said barrel between said offset members, lead feeding mechanism associated with said tube, said tube having resilient gripping means to be engaged between said offset members to detachably secure said tip 80 to said barrel.

5. A mechanical pencil comprising a barrel, a shell mounted in said barrel, said shell provided with inwardly offset portions, a detachable tip mounted at one end of said barrel, a lead receiving and feeding tube secured to said tip, and friction means on said tube arranged to coact with said offset portions to frictionally hold said tube and tip in operative position.

6. A mechanical pencil comprising a barrel, a shell mounted in said barrel, said shell provided with inwardly offset elongated members, a detachable tip mounted at one end of said barrel, a lead receiving and feeding tube secured to said tip, and friction means at the inner end of said tube arranged to coact with said offset members to frictionally hold said tube and tip in operative position.

In witness whereof, I have hereunto subscribed my name.

JOHN C. WAHL.
